BOTTLE-CORKING APPARATUS

Gilbert Tabard, Villemomble, France, assignor to Societe
d'Exploitation des Ateliers Mecaniques A. Tabard,
Villemomble, France

Filed July 13, 1973, Ser. No. 378,912

Claims priority, application France Jan. 15, 1973

Term of patent 14 years

Int. Cl. D8—05

U.S. Cl. D8—51

FIG. 1 is a top plan view of a bottle-corking apparatus showing my new design;

FIG. 2 is a side view. The opposite side view is substantially the same;

FIG. 3 is a bottom plan view;

FIG. 4 is one end view; and

FIG. 5 is the opposite end.

I claim:

The ornamental design for a bottle-corking apparatus, substantially as shown and described.
